UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

ANTIFRICTION SIDE BEARING.

1,244,781.

Specification of Letters Patent. Patented Oct. 30, 1917.

Application filed March 29, 1917. Serial No. 158,276.

To all whom it may concern:

Be it known that I, JOHN M. ROHLFING, residing at St. Louis, Missouri, and being a citizen of the United States, have invented 5 certain new and useful Improvements in Antifriction Side Bearings, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction 15 shown and described, as it is obvious that various modifications thereof within the scope of the claims will occur to persons skilled in the art.

In said drawings:

20 Figure 1 is a plan view of my improved side bearing;

Fig. 2 is a vertical transverse section taken on the line 2—2 of Fig. 1 and illustrating the upper and lower runways associated with 25 one set of operating rollers; and

Fig. 3 is a longitudinal vertical section taken on the line 3—3 of Fig. 1 showing the plurality of roller sets in normal positions.

30 My invention relates to anti-friction bearings of the type that is well adapted for use as the side bearings of railway cars.

One of the objects is to provide a suitable casting for attachment to one of a pair of co- 35 operating bolsters of a railway car and to mount in said casting one or a plurality of sets of rollers, in each set one roller being revolvably mounted upon another. The arrangement is such that one of the rollers of 40 each set is adapted to normally rest upon one of the runways and have such co-operation therewith as to cause the set to be automatically centered by gravity, the set being, however, capable of coming into contact 45 with another bolster so that the set or sets of rollers may be caused to engage and roll upon the other runway.

When the rollers are caused by the last 50 mentioned bolster to ride along the runway to which they have been carried, the roller engaging that runway is brought to a point of stoppage by suitable means after a pre-determined amount of rolling, but the roller mounted upon the arrested roller is adapted 55 for continued and uninterrupted revolving

under the influence of the bolster actuating the rollers. As a result, the outer roller, which is the one engaged by the actuating bolster, is always free to revolve and thus there is an avoidance of the danger of this 60 roller acquiring flat spots, which often occur in roller side bearings, impairing their efficiency. If for any reason the roller riding on the runway becomes jammed, it is obvious that the outer roller with its unrestricted capability of independent rotation, 65 will still allow the roller side bearing to function without detriment to itself or the bolster that is actuating it.

Where there are a plurality of rollers, 70 each set has its independent zone of travel and may be inserted in the side bearing casing at one of the ends thereof. Such insertion is capable of taking place before the positioning of wearing plates which furnish 75 the contact surfaces of one of the runways, and after the wearing plates have been properly combined with the casing they co-operate with the terminals of the other runway to prevent accidental escape of the 80 roller sets.

Such features as have not already been referred to but become manifest hereinafter are, of course, to be regarded as coming 85 within the scope of the present invention.

Referring specifically to the drawings, 1 indicates, in dot and dash lines, a body bolster, and 2 the upper surface of a truck bolster or side bearing carried thereby, positioned below the body bolster. 3 indicates a 90 side bearing casing or housing attached to body bolster 1 by fastening means adapted to pass through the attachment lugs or flanges 4 which project laterally from the upper portions of the side walls 5 of casing 95 3. The upper portions of side walls 5 are connected by an overhead wall 6 which is provided with ledge-like portions 7 to the undersides of which are riveted or otherwise secured wearing strips 8. The lower 100 edges of side walls 5 of casing 3 are in-turned to form separated flanges 9 that constitute a lower track or runway positioned directly under laterally spaced wearing plates 8. Each flange 9 is upturned at its 105 ends and at a centrally intermediate location, thereby forming end stops 10 and an intermediate stop 11. Between the intermediate and end stops, the sections of the track forming flanges 9 are each depressed toward 110

the points central to the end and intermediate stops.

Between the intermediate stop 11 and each end stop 10 is a set of rollers each comprising a roller pin 12 having its opposite ends projected between track-forming flanges 9 and the vertically spaced wearing strips 8 and an outer roller 13 revolvably mounted on roller pin 12. Due to the downwardly and 5 reversely sloping upper faces of each section of flanges 9, the roller sets automatically center themselves by gravity when the outer rollers 13 are unaffected by the truck bolster side bearing 2, being at such times spaced 10 slightly below the wearing strips 8. The roller sets comprising roller pin 12 and outer roller 13 are inserted into casing 3 through the open ends of the casing before wearing strips 8 are secured to the ledge 15 portions 7 of the overhead wall 6, and after the insertion of the rollers the said wearing strips are secured in place as illustrated. As best shown in Fig. 3, the terminals of wearing plates 8 are so juxtaposed to the curved 20 upturned ends 10 of the bottom flanges 9, that roller pins 12 are incapable of passing through the space between the terminals of 25 said wearing plates and end stops 10, the diameter of roller pins 12 being greater than 30 the space between such terminals.

The body bolster 1 and the truck bolster provided with the side bearing 2 are vertically moved together at such times as the car careens, as it does when negotiating a curve 35 in the track. At such times, truck side bearing 2 engages the outer rollers 13 forcing them upward relatively to the overhead wall 6 of casing 3. The internal diameters of 40 rollers 13 are greater than the external diameters of roller pins 12 so that the outer rollers 13 are ring-like and contact when in 45 their normal position with the top portions of roller pins 12. It will, therefore, be seen that outer rings or rollers 13 are suspended from roller pins 12.

When the body bolster 1 moves downwardly toward the truck bolster to cause the outer rings or rollers 13 to approach wall 6 of casing 3, said outer rollers tangentially 50 engage the inner pin rollers 12 on their under sides and cause said pins to be carried from the track-forming flanges 9 into engagement with the under surfaces of the 55 wearing strips 8. During the relatively opposite transverse swiveling of the body and truck bolsters, roller pins 12 are caused to ride or roll along the wearing strips 8 until they engage stops 10 and 11, the outer rollers 13 rolling with inner rollers 12, whereupon 60 said pin rollers become arrested. As will be appreciated from Fig. 2, the outer rollers 13 will have passed up into the central longitudinal pocket 14 formed in the overhead wall 6, but not sufficiently to roll upon 65 the wall 6, and being located between wear-

ing strips 8 will not roll upon these. It consequently becomes apparent that outer rollers 13 are unrestrained as to their revolution and, as long as there is relative lateral movement between the body and truck 70 bolsters, will continue to freely revolve and are in no danger of acquiring flat spots which subsequently would interfere with their perfect functioning.

As the car rights itself, the upper and 75 lower bolsters 1 and 2, respectively, vertically separate, and roller pins 12 will automatically roll to the lowermost depressed portions of flanges 9 to assume their normal 80 centered locations.

It will be seen from Fig. 2 that the roller annulus 13 is provided with a relatively thick shell, that roller pins 12 are solid and have sufficient diameter to give them a rugged nature, and that the wearing plates 85 8, especially when combined with the ledge portions 7 of the casing, form thick reactance portions in the casing. As a consequence, when rollers 12 and 13 are carried upwardly so that the ends of roller pins 12 90 engage the wearing plates, there is a combination of rugged elements well adapted to withstand the compression set up by the relative approach of the body and truck 95 bolsters. Roller pins 12 may be, if desired, tubular, retaining their resistive qualities through the well known strength of tubes.

It will also be seen that there are few parts and that these are simple and may be cheaply produced, thereby producing an inexpensive and highly efficient roller side bearing, and that the roller rings provide 100 bearings for the roller pins in the nature of endles tracks, laid progressively in the path of movement of the roller pins.

What I claim is:

1. In combination in a side bearing, a casing having an open end, said casing being adapted to be fixedly positioned on a bolster and comprising a track, wear members vertically spaced from said track, and an anti-friction device insertible through said open end of said casing and having roller ends projected between said track and wear members and transferable to either to roll 110 thereon.

2. In combination in a side bearing, a casing provided with a track and a permanent opening, suitably retained wear members vertically spaced from said track, and 115 rollers one revolvably mounted on the other and passable through the permanent casing opening while assembled, the mounting roller being adapted to roll on either said track or wear members.

3. In combination in a side bearing, a casing provided with an end opening and a track, wear members spaced from said track, and independently revolvable rollers mounted one upon the other, said rollers 125 130

- and wear members being insertible through said end opening, the mounting roller projecting between said track and wear members and being movable to either to roll thereon, said rollers being normally centered by gravity. 5
4. In combination in a side bearing, a casing with an end opening and having a track provided with stops, and rollers mounted one upon the other and insertible through said end opening, the mounting roller being adapted to roll on said track and to be arrested by said stops, the mounted roller being adapted under the influence 10 of an extraneous bearing to thereafter continue revolving. 15
5. In combination in a side bearing, a casing having a permanent opening and being adapted to be fixedly positioned on a bolster, interconnected rollers passable through said opening while assembled to be mounted in said casing and adapted to roll so as to travel in unison, and means for causing a part of said rollers to cease rolling. 20
6. In combination in a side bearing, a casing provided with vertically spaced runways, a roller projecting therebetween, a second roller surrounding the first roller and containing an enlarged passage therefor permitting displacement of said second roller transversely of the first roller, said first roller being adapted to roll on either runway, means limiting the rolling of said first roller permitting the continued revolution 25 of the second roller. 30
7. In combination in a side bearing, a casing provided with vertically spaced runways, a roller projecting therebetween initially ridable on one of said runways, a second roller loosely surrounding the first roller and having an internal diameter materially larger than the diameter of the first roller and being normally supported from said first roller and adapted under applied 35 force to move the first roller into rolling contact with the other runway and to so support it. 40
8. In combination in a side bearing, a casing provided with vertically spaced lateral projections one forming a track, a separately formed wearing strip secured to the other lateral projection, and a roller having an end projected between said track and wearing strip adapted to roll on either, the 45 terminals of said track and strip being so juxtaposed as to prevent removal of said roller, the roller being adapted to be inserted and removed when said strip is not in place. 50
9. In combination in a side bearing a casing open at both ends and having vertically spaced lateral projections some forming a track, stops in the end and intermediate portions of said track, wearing strips on 55 some of said lateral projections that are spaced from the track, and rollers having ends adapted to roll on said track and strips between said intermediate and end stops, said rollers being adapted to be inserted through the casing ends when the 60 wearing strips are not present and held from escape by said strips and end stops. 70
10. In combination in a side bearing, a casing comprising spaced side walls with permanently attached track-forming flanges and an overhead wall connecting the side walls, wearing strips secured to the overhead wall above said flanges, a roller projecting between said flanges and strips normally resting on said flanges, a second roller 75 revolvably mounted on the first roller with its periphery out of alignment with said wearing strips, and means for arresting the travel of said first roller, said second roller being adapted to be revolved after the first 80 roller has been arrested in its travel. 85
11. In combination in a side bearing, a casing comprising spaced side walls having integral track-forming members and being connected by an overhead wall, spaced wearing strips underlying the latter wall over said track members and each establishing an unbroken path for roller-travel, a roller extending between said members and strips and normally resting on the former, a second roller 90 revolvably mounted on the first roller adapted under applied force to cause the first roller to move to and roll on said strips to a point of stoppage and to continue revolving after the stoppage of the first roller. 95
12. In combination in a side bearing, a casing having an end opening and spaced track-forming members, spaced wearing strips positioned over said track members, a roller extending between said track members and strips, normally resting on the former, a second roller revolvble on the first roller adapted under applied force to move with and cause the first roller to move to and roll on said strips to a point of stoppage, the 100 second roller being capable of revolving thereafter, said rollers while assembled and said wearing strips being inserted through said casing opening. 105
13. In combination in a side bearing, a 115 casing having an opening and permanently fixed spaced track-forming members, spaced wearing strips positioned over said track members, a roller extending between said track members and strips, normally resting on the former, a second roller revolvble on the first roller adapted under applied force to move with and cause the first roller to move to and roll on said strips to a point of stoppage, the second roller being capable 120 of revolving thereafter, said rollers being inserted through said casing opening while assembled and also being adapted to cooperate with said track members to become 125 centered by gravity. 130

14. In a bolster side bearing having a casing having open ends and provided with a plurality of track members spaced apart, and compound rollers adapted to be inserted through said open ends of the casing and arranged between said track members, said rollers comprising each a track engaging roller element and a roller bearing sleeve portion providing a continuous bearing for said track engaging roller.

15. In a bolster side bearing provided with a casing having an opening and a plurality of track members spaced apart, and compound rollers adapted to enter said casing through said opening and being arranged between said track members and also being held from escape thereby, said rollers comprising each a track engaging roller ele-

ment and a roller bearing sleeve carried thereby, said sleeve being adapted to provide a bearing for portions of said track engaging roller.

16. In a bolster side bearing, a casing having a plurality of track members spaced apart and provided with juxtaposed terminals subject to separation, compound rollers movably mounted between said track members and comprising each a track engaging roller element held from escape by said track member terminals and carrying a bearing sleeve, said bearing sleeve being adapted to support the roller in one of its track engaging positions.

In witness whereof I have hereunto set my hand.

JOHN M. ROHLFING.
